UNITED STATES PATENT OFFICE.

CHRISTIAN AALBORG, OF WILKINSBURG, PENNSYLVANIA, ASSIGNOR TO WESTINGHOUSE ELECTRIC & MANUFACTURING COMPANY, A CORPORATION OF PENNSYLVANIA.

THERMAL CONTROL DEVICE.

Application filed September 3, 1919. Serial No. 321,459.

My invention relates to thermal control devices and particularly to electrically operated types of such devices.

The object of my invention is to provide a compact and reliable means that shall be simple and easy to construct, for controlling the temperature of a water tank or some similar heat-storage device.

Ordinarily, an electrically heated apparatus embodies a heating element composed of iron wire or heavy iron grids. The temperature of the apparatus is kept approximately constant by alternately closing and interrupting a circuit including the heating element.

In practicing my invention, I provide a compact control device comprising a helically-wound bi-metallic spring, a motor and a switch, all enclosed in a dust-proof casing.

In the accompanying drawings, Fig. 1 is a side sectional elevation, and Fig. 2 an end elevation of the device; Fig. 3 is a side elevation and Fig. 4 an end elevation of the thermostat; Fig. 5 is a diagrammatic view 25 of a system embodying my invention; and Fig. 6 is a front elevational view of the snap switch taken along the line VI—VI.

In Figs. 1 and 2, a casing 1 encloses a device comprising a bi-metallic helical spring 2, a switch 3 and a motor 4. The bi-metallic spring 2 extends into a housing 5 of the casing 1 and is rigidly fastened, at one end, to a cylindrical rod 6 which, in turn, is fastened, at the opposite end, to a movable member 7. The movable member 7 may be adjusted by a handle 8. Friction between the movable member 7 and a fixed member 9 serves to hold the former in any position to which it may be adjusted by means of the handle 8. A movable contact member 10, supported by the free end of the bi-metallic spring 2, is adapted to engage the contact end of the one or the other of screw members 11 and 12. Each of the members 11

45 and 12 is surrounded by a coil 13. The switch 3, comprising a blade 14, jaws 15, 16, 17, 18 and 19 and a spring 20, is actuated by the motor 4, through gearing 21. The housing 5 is disposed in a heat-storage device 22.

Figs. 3 and 4 show more clearly the bi-metallic helical spring 2 and its housing 5.

In Fig. 5, the arrangement of the parts is indicated approximately as they are located. Three conductors 23, 24 and 25 are

connected to the switch jaws 15, 16 and 17, 55 respectively. The motor 4 is connected between the switch jaw 16 and the movable contact member 10. The switch-jaw 16 is employed for convenience merely as a binding post. The switch jaws 17 and 18 are connected by a conductor 18, and the switch jaws 15 and 19 are respectively connected to the outer ends of the respective coils 13. The other end of each coil 18 is connected to the contact end of the member upon which 65 it is supported. A resistor 26 of the heat-storage device 22 is connected between two conductors 23 and 24. Two conductors 24 and 25 are connected to a source of current (not shown).

Fig. 5 shows the position of the switch 3 and the movable contact member 10 while the heating element 26 of the heat-storage device 22 is being energized.

As the temperature in the heat-storage device 22 increases beyond a predetermined value, the bi-metallic helical spring 2 will expand and, being helically wound, will tend to move the contact member 10 to engage the contact face of the member 12. The corresponding coil 13 thus becomes energized and serves to hold the contact member 10 in engagement with the contact face of the member 12, thereby completing the circuit of the motor 4. The motor 4 operates, 75 through the spring 20, to actuate the switch 3, thereby opening the circuit of the motor 4 and that of the heating element 26 of the heat-storage device 22. The switch blade 14 now engages the switch jaws 17 and 19. As 80 the temperature of the device 22 decreases to a predetermined value, the movable member 10 engages the contact face of the member 11 and thus completes the motor circuit. The switch 3 is again actuated, and 85 the heating element 26 is again energized to heat the device 22.

The operating mechanism of the snap switch 3 comprises the spring 20, a shaft 30 having a pinion 31 disposed thereon, a latch 100 32 that is controlled by the pinion 31, and a stationary stop 33 of ratchet-shape that co-operates with the latch 32 to limit the movement of the switch to a right-angle turn.

One end of the spring 20 is secured to the structure of the blade 14 and the other end is secured to the shaft 20. As the shaft 20

is turned, the pinion 31 moves the latch 32 in its guideway 34 to move a dog portion 35 beyond the end of a tooth 36 on the ratchet-shaped stop 33. As the dog portion 35 clears the end of the tooth 36, the tensioned spring 20 moves the blade 14 to its other position. The blade 14 and the operating mechanism comprising the movable elements, namely, the latch 32 and the guideway 34, are mechanically secured and turn together to the next position of the switch. The dog portion 35 engages the next tooth 37 and precludes further movement of the switch until the spring is again tensioned.

15 Supporting bracket 38 is provided for supporting the switch 3 and the motor 4 in the casing 1.

It will be understood that my invention is not limited to the structure herein set forth, 20 as various modifications may be made without departing from the spirit and scope of the appended claims.

I claim as my invention:

1. A unitary heater controller of the bayonet type comprising a casing having a portion adapted to be inserted in a heat-storage 25 receptacle, to be subjected to the heat therein, a thermal responsive element disposed in said portion, a supporting and adjusting means for the thermal responsive member mounted on said portion, a supporting bracket supported by the encasing portion, a switch and an operating means therefor controlled by the thermal responsive means 30 and disposed on the supporting bracket, and a cover member removably mounted on said casing for enclosing said thermally responsive element, supporting and adjusting means, supporting bracket, switch and operating means therein.

2. A unitary heater controller of the bayonet type comprising a casing having a portion adapted to be inserted in a heat-storage receptacle to be subjected to the heat therein, 45 a snap switch, rotatable means for actuating said switch, a supporting bracket

secured to said casing for supporting said snap-switch, and rotatable means, a thermally responsive element disposed in said casing portion for controlling said rotatable means in accordance with the temperature of the storage receptacle, and a supporting and adjusting means for said thermally responsive member mounted on said casing.

3. A heater controller comprising a casing having a portion adapted to be subjected to the temperature of a device to be controlled, a circuit controlling device, means for actuating said controlling device, a bracket mounted on said casing for supporting said circuit controlling device and said actuating means, a thermally responsive element disposed in said portion for controlling said actuating means in accordance with the temperature of the device to be controlled, and a supporting and adjusting means for said element for controlling the temperature at which said controller is operable.

4. A unitary heater controller for regulating the temperature of a heat-storage receptacle comprising a casing, a portion of which is adapted to be inserted in said receptacle, a switch, a motor, a supporting bracket mounted on said casing for supporting said switch and motor, a spring member operatively engaging said switch and motor adapted to store energy from the motor for causing the switch to operate in response to rotation of the motor with a snap action, a thermally responsive element located in said portion for controlling the circuit connections of said motor in accordance with the temperature of said receptacle, and a cover member secured to said casing for enclosing the switch, spring, supporting bracket and thermally responsive element therewithin.

In testimony whereof, I have hereunto subscribed my name this 26th day of Aug., 1919.

CHRISTIAN AALBORG.
